UNITED STATES PATENT OFFICE.

BRUCE BORLAND, OF CHICAGO, ILLINOIS.

LOCK.

1,075,139.

Specification of Letters Patent.

Patented Oct. 7, 1913.

Application filed February 8, 1906, Serial No. 300,074. Renewed March 13, 1913. Serial No. 754,127.

To all whom it may concern:

Be it known that I, BRUCE BORLAND, a citizen of the United States, residing at Chicago, in the county of Cook and State 5 of Illinois, have invented certain new and useful Improvements in Locks, of which the following is a specification, reference being had therein to the accompanying drawings.

This invention relates to improvements 10 in multiple key locks particularly adapted for use with the drawers or boxes of safety deposit vaults, and the like, although certain features thereof are applicable for use with other locks.

15 The invention consists of the organizations and arrangements of parts herein-after particularly described and then pointed out in the appended claims.

In the accompanying drawings—Figure 20 1 is a view of the lock in elevation with the cover removed and showing the bolt in its shot or locked position; Fig. 2 is a similar view with the locking bolt in its shot 25 position, the bolt locking dog being released; Fig. 3 is a like view showing the locking bolt retracted; Fig. 4 is a section on the line 4—4 of Fig. 1; Fig. 5 is a plan view of the lock showing the primary tumblers disengaged from their operating pinions to 30 reset the lock, that is to change the combination and adapt the same to a new key; Fig. 6 is a detail perspective view, diagrammatic in character, of the primary and master tumblers, and certain associated 35 parts, showing such tumblers in their normal or locking positions; Fig. 7 is a similar view of the tumblers showing the parts in their unlocking positions; Fig. 8 is a sectional view on the line 8—8 of Fig. 3; Fig. 40 9 is a detail view of the sliding plate on which the primary tumblers are mounted; Fig. 10 is a detail view of one of the washers associated with the master tumblers; Fig. 11 is a similar view of the one of the 45 washers for the primary tumblers and their operating pinions; Fig. 12 illustrates the depositor's key used for actuating the primary tumblers; Fig. 13 is a view of an auxiliary key for lining up the primary 50 tumblers; Fig. 14 is a detail of the guard's key employed for actuating the master tumblers; Fig. 15 is an end view of the same; Fig. 16 is a diagrammatic view showing the arrangement of the groove in the guard's 55 key; Fig. 17 is a similar view of the key

employed in resetting the lock; Fig. 18 is a view of a key employed for alining the master tumblers; Fig. 19 is an end view of the same; Fig. 20 is a longitudinal sectional view of such key; and Fig. 21 is a similar 60 view of an auxiliary key.

Referring to the drawings, 25 indicates a suitable case which is shown as rectangular and provided at one end with a bolt opening 26. A cover plate 27 is suitably 65 secured to the case 25 and is provided near its rear end with a key sleeve 28 and between such sleeve and the front end of the lock with a second sleeve 29. Suitable openings 30 passing through the cover and case 70 are provided for screws to secure the lock in position.

The locking bolt 31, which extends through the opening 26, is provided within the case with a head 32 adapted when the 75 bolt is thrown to abut against the front end of the lock case, as shown for example in Fig. 1. This head is provided at its upper end with a rearwardly extending flat tail 33, located adjacent the cover plate, 80 Figs. 1 and 4, and which is in the form of a rack bar having its teeth extending inwardly. Beyond the rack teeth the tail 33 is provided with a curved or concave portion 34. At the bottom of the case the bolt 85 31 is provided with a second tail 35 which rests against the back wall of the case and to which is pivoted, as at 36, a locking dog or latch 37. The thickness or depth of the dog is substantially the distance between 90 the tail 35 and the cover plate 27. The rear or locking end of the dog 37 is adapted to engage, when the bolt is in locked position, Fig. 1, with a stop consisting in the present instance of a shoulder 38 formed in the 95 lock case. Between the shoulder 38 and the bottom wall of the lock is a longitudinal cavity 39 into which the locking end of the dog slides when the bolt 31 is retracted, as shown in Fig. 3, a shoulder 40 on the dog 100 then coöperating with the stop 38 to limit the retractive movement of the bolt. The front end of the dog is in the form of a rack bar, and at the rear of the teeth thereof is an enlarged tooth or lug 41. The dog 105 37 may be held in its locking position by gravity, as the pivot 36 is back of the center thereof, but preferably a suitable spring is employed for the purpose, such as the leaf spring 42, the front end of which is fixed 110

to the rear end of the bolt tail 35 while its other end reacts against a pin 43 on the dog.

The rear portion of the lock case is made solid, as at 44, having a cavity 45 which is open at its front side, as at 46. The rear wall of this cavity is provided with a recess 47. The back wall of the case at the bottom of the cavity 45 is stepped up as at 48, Fig. 4, and a key guide consisting of a post 49 is fixed in the stepped up portion 48 and extends into the circular key opening of the sleeve 28 concentric with such opening. The post 49 is provided with a guide stud 50 at its free end. A pinion 51 is located in the bottom of the cavity 45 and above such pinion are rotatable tumblers 52, which are herein designated master tumblers, four of such tumblers being shown in the present instance. The pinion 51 and tumblers 52 are concentric with the post 49 and are separated from each other by washers 53 into the opening of each of which extends, as shown in Fig. 4, a hub portion 54 of a tumbler, the washers thus providing pivot supports for the tumblers and keeping them centered. By reason of the friction between the washers and tumblers the latter are held against accidental rotation. A similar washer is located between the pinion 51 and the bottom of the cavity 45. These washers fit the cavity 45 snugly and are provided with tongues 55 (Fig. 10) which project into the recess 47 and prevent movement of the same. Each of the tumblers 52 and the pinion 51 is provided with a central opening through which the key post 49 extends, such openings being in alinement and of greater diameter than the post. Each opening is provided with inwardly directed teeth and at a certain point therein a tooth is omitted providing a space 56. Each tumbler 52 is in the form of a peripheral gear provided with at least one or in some instances two missing teeth. For example, the upper and second tumblers 52, as shown in Figs. 6 and 7, each has one tooth missing providing a recess 57, while the third and fourth each has a recess 57 and a recess 58.

As shown in the drawings, the pinion 51 and tumblers 52 project through the opening 46 in the wall of the cavity 45 and at this point the washers 53 are cut away as at 59 so that the teeth of the tumblers will 55 project beyond the same.

A post 60 is pivoted, as shown in Fig. 4, in the back wall and cover 27 of the case and this post is provided at its lower end with a segmental cam or eccentric 61. A pinion 62 is fixed to the post above the cam 61 so as to engage the pinion 51. Above the pinion 62 the post is provided with a block providing a cam 63 which is radial to the post and has a rounded nose. The cams 61 and 63 are at a fixed angle with relation

to each other being at substantially a right angle in the present instance. The cam 63 is substantially the height of the combined thickness of the tumblers 52 and washers 53, as shown in Fig. 4, and at its rear side has a pair of teeth or fins 64 and 65 which are radial to the post 60. The teeth 64 and 65 are in line with spaces between the teeth of the pinion 62. The teeth 64 and 65 are designed to enter the recesses in the tumblers 52 when the recesses are properly alined to receive the same to permit of the turning of the pinion 62 in one direction or the other for the purposes hereinafter explained.

The rear wall of the case in line with the sleeve 29 is provided with a stepped up portion 66 formed with a socket 67 in its bottom. A wall 68 is formed in the lock case to provide a circular well 69 having an opening in its front side. A key post 70 is seated in the sleeve 29 and is provided with a reduced extension 71 passing through the well 69 and having its end seated in the socket 67. A key groove passes through the post and the extension 71, as shown in Fig. 4. The post 70 has fixed thereto just within the cover 27 a pinion 72 having a concentric toothless portion 73 which is adapted to coöperate with the curved portion 34 of the bolt tail 33, as hereinafter described. A series of five gears 74 having central alined openings 75, through which the extension 71 passes, is located in the cavity 69 being spaced apart by suitable friction washers 76, the gears being pivoted thereon in the same manner as the tumblers 52. Each of the gears 74 has a key opening 77, one of the walls of which is parallel with a line radial to the gears while the other wall is stepped as at 78, five steps being provided in the present instance and the stepped portion extending from the outer end of the straight wall back to the opening 75 so that the steps decrease in distance from the center of the tumbler as the stepped portion recedes to the opening 75. Each of the gears is provided with a solid or toothless portion 79, to limit the movement of such gears to such distance as is required for the proper operation of the lock.

A sliding plate 80 is adapted to slide on the back wall of the case and this plate is provided at suitable points with elongated slots 81 through which pass guide screws or studs 82 fixed to the case. This plate is cut out, as at 83, to clear the wall 68 and at its rear end is bifurcated at 84, the cam 61 being located in the bifurcation. At its front end the plate has fixed thereto a post 85 which in the present instance extends to the cover 27 having its end flat to slidingly engage such cover. Rotatable toothed tumblers 86, corresponding in number to the gears 74, and normally in engagement there-

with, are pivoted on the post 85. These tumblers are spaced apart by extensions of the washers 76. Each of the tumblers 86 at a certain point has a missing tooth to provide a slot 87, such slots being designed to be brought into register as hereinafter described, and the space between one pair of the teeth of each tumbler is enlarged to provide a rectangular recess 88. A post 89 is fixed to the back wall of the case in such position that when the recesses 88 are in alignment and the plate 80 is moved forward the slots 87 will engage the post thereby permitting of the movement of the plate and 15 the disengagement of the tumblers 86 from the gears 74.

A pinion 90 is pivoted at the end of the post 85 being provided with a slot similar to the slots 87 of the tumblers and a recess 20 similar to the recesses 88 of such tumblers. This pinion is adapted to mesh with the gear 72 and is provided with a toothless concave portion 91 at its periphery adapted to co-operate with the convex toothless portion of 25 the pinion 72, by which the pinion 90 is locked against rotation.

The key for operating the tumblers 86 to bring the slots 87 thereof into alignment to receive the lug 41 of the bolt locking dog 30 and which is designated the depositor's key, is illustrated in Fig. 12. This key, 92, consists in the present instance of a flat plate of suitable size to fit in the key slot provided therefor, and the bits 93 thereof are so 35 arranged as to co-operate with the steps of the key openings in the gears 74. When the key is inserted in the lock and turned to the right or clockwise in the direction of the arrow in Fig. 6 each gear is picked up and 40 moved as the bit of the key associated with such gear comes into engagement with the step with which it is designed to co-operate. The slots 87 are normally out of alignment (Fig. 6), and the movement of each gear 45 is just sufficient, when the key is turned the proper distance which in the present instance is one half a rotation, to bring all the slots into alignment (Fig. 7) and opposite the lug 41 of the dog. During this 50 operation the toothless portion of the gear 72 moves past the toothless portion of the pinion 90 until at the proper moment the first advancing tooth of the gear 72 comes into engagement with the first tooth of the 55 pinion 90 to move the pinion the proper distance to line up its slot 87 with the slots 87 of the tumblers (Fig. 7). The key 92 has a notch 94 adapted to receive a shoulder 95 at the entrance of the sleeve 29 in the 60 usual manner to prevent withdrawal of the key while the pinions are being turned.

The guard's key associated with the master tumblers 52 consists of a tubular body portion 96 into which extends a cylindrical shell 97. The portion of this shell

extending outside the body portion is toothed to fit the central teeth of the openings in the tumblers 52 and is of a length equal to the combined thickness of the pinion 51 and the tumblers 52. A longitudinal slot 98 extends the length of the toothed portion of the shell and this slot within the tubular body is made sinuous, as at 99, and as shown in Fig. 16. The tumblers 52 are normally in such position that the recesses 57 are out of alignment. When this key is inserted on the guide post 49 the stud 50 thereof enters the slot 98 and while the straight portion of such slot passes along the stud the key is held from turning. As soon, however, as the key pinion engages the first tumbler 52 the sinuous portion of the slot comes into engagement with the stud 50 so that as the key is turned the tumbler is rotated, and as each successive tumbler is picked up owing to the course of the slot it is turned in unison with the preceding tumblers so that when the last tumbler is engaged and turned the slots 57 of the tumblers are aligned and in position to receive the tooth 65 when the pinion 62 is turned by the action of the pinion 51.

The normal or locked positions of all the parts are shown in Fig. 1. To unlock the lock the depositor's key is inserted and turned clockwise about one half a rotation. This brings the slots 87 of the tumblers 86 into position to receive the lug 41. Further movement of the key is prevented by reason of the fact that although the first advancing tooth of the pinion 72 comes into engagement with the end tooth of the bolt tail 33, the bolt is still locked by the dog.

The guard's key is now inserted in the lock to release the locking dog 37. As soon as 105 the guard's key has entered the lock far enough to engage the pinion 51 the key is turned clockwise, this being permitted by the terminal of the key slot 99, moving the pinion 62 contra-clockwise and thrusting the 110 cam 63 against the end of the dog 37, the tooth 65 entering the aligned slots (Fig. 3) as the tumblers 52 and pinion 51 are turned together. This disengages the dog from the shoulder 38, as shown in Fig. 2, the lug 115 41 entering the aligned recesses 87 in the tumblers 86. Until the slots or gates of the tumblers 52 are lined up movement of the cam is prevented owing to the obstruction presented to the tooth 65 by the teeth of 120 the tumblers.

The object in having the tooth 65 aligned with a space in the pinion 62 is to bring it opposite to the aligned slots in the tumblers 52 such slots being provided by the omission of a tooth which if present would of course correspond with a space in the pinion 62.

The preliminary rotation of the pinions 74 by the key 92 to bring the tumblers 86 130

into alined position, carries the toothless portion of the pinion 72 out of engagement with the concave portion 34 of the bolt tail 33, and the teeth of the pinion 72 being now in engagement with the teeth of the bolt tail, further rotation of the key 92 retracts the bolt, the rear end of the dog entering the cavity 39, as shown in Fig. 3. During the retraction of the bolt the tumblers 86 are rotated in a contrary direction and as they coöperate with the teeth on the locking dog motion is also imparted to the bolt through such bolt tail. This insures an even movement of the bolt and provides a stronger construction, that is one less liable to breakage.

In locking, the operation heretofore described is reversed, but owing to the engagement of the pinion 90 and tumblers 86 with the teeth of the bolt dog 37, such tumblers are rotated in unison, until the parts assume the positions of Fig. 2. Then as the key 92 moves back through the key openings 77 into engagement with the straight wall of each pinion 74, the tumbler associated with the pinion is restored to its original position by the movement of the pinion 74. This insures the restoration of the tumblers 86 to their proper relative positions. The straight wall of each key opening 77 is offset from the radial one half the thickness of the key so that the key will bear squarely against such wall, as shown in Fig. 1.

In unlocking, both keys are necessary, as the guard's key is required to release the locking dog and this cannot be done until the depositor's key has set the tumblers into unlocking position. For locking, however, the guard's key is not necessary as when it is withdrawn the tumblers 52 are restored as well as the cam, and then the bolt may be thrown simply by the depositor's key. This key can not be withdrawn, however, until the bolt is thrown.

When it is desired to change the key 92 for another depositor's key, that is to reset the lock or change its combination, the old key 92 is inserted in the lock and the tumblers thrown into position to bring the slots 87 thereof in alinement which also alines the slots 88. A resetting key 100 which will be held by a custodian such as the manager of the vault, and which is similar to the guard's key, but having its sinuous portion of different arrangement, as indicated by 101, Fig. 17, is inserted into the key sleeve 28. The groove of this key is so arranged as to bring the slots 57 of the two upper tumblers 52 in Figs. 6 and 7 into alinement with the slots 58 of the lower tumblers so that when the key engages the pinion 51 and is turned contra-clockwise the tooth 64 will enter the alined gates or slots as the pinion 62 is turned. This action moves the cam 61 against the front

wall of the bifurcation 84 of the plate 80 sliding such plate forward and disengaging the tumblers 86 from the gears 74. The customer's key 92 is now turned to locking or normal position and withdrawn and the new customer's key is then inserted. This key is now turned so as to move the gears 74 into such position as to bring the first tooth of the pinion 72 into engagement with the end tooth of the bolt tail 33, which is the position of the key under normal conditions when the slots 87 of the tumblers 86 are alined. The key 100 is now turned to retract the sliding plate thereby throwing the tumblers 86 into engagement with the gears 74, and the lock can then only be operated by the new key until the combination is again changed.

The parts 74 and 86 constitute two-part tumblers and by moving the pack composed of the parts 86 by sliding the plate 80 to disengage this pack from the pack composed of the parts 74 these tumblers may be reset to different combinations for different customer's keys as above set forth and the packs then reengaged by reverse movement of the plate so that the lock is set upon a particular customer's key, the movements of the plate to engage and disengage the packs being accomplished by the cam or eccentric 61 acting on the plate and which is locked and unlocked and operated for these respective purposes by the manager's resetting lock, the movement of the key of this latter lock being transmitted to the eccentric 61 through the intermediate pinions 51 and 62. The manager's lock constitutes a supplemental safety lock to prevent unauthorized resetting of the combination.

In the event that the tumblers 86 are moved out of their proper relative positions, owing to an attempt to pick the lock, for instance, I employ a key 102 such as shown in Fig. 13, for restoring the same. This key is provided with an elongated bit 103. By inserting this key in the lock and turning the same contra-clockwise the straight walls of the key openings 77 in the gears 74 will be placed in alinement, this being the condition of the lock when the gears are in normal positions, and this restoring of the gears properly positions the tumblers actuated thereby.

In the event that the tumblers 52 accidentally become jolted or thrown out of proper position, these tumblers may also be restored through the medium of a suitable key 104 substantially like the guard's key except that the cylindrical shell 105 terminates just inside the tubular body its projecting portion being toothed as at 106. The slot 107 of this key, such slot being straight, is out of engagement with the guide pin 50 when the key is in the lock, so that the key may be turned freely in

either direction. This key has an enlarged tooth 108 designed to enter the recesses 56 in the tumblers 52, and is extended beyond the key as shown in Figs. 18 and 20. It is to be understood that when the tumblers 52 are in proper positions the spaces 56 are in a definite relation to one another. If when the proper customer's key is in and turned to unlocking position, upon inserting the 5 guard's key in the lock and turning the same it will not release the dog, it will then be known that the tumblers have been moved and are not in proper position. The key 104 is then entered on the post 49 and 10 turned until the end of the tooth 108 finds the recess 56 in the first tumbler and so on until it engages with and enters the recess 56 of each tumbler. The key is then turned until its slot 107 is in line with the stud 50. The key may then be withdrawn. 15 With this key it may happen that when withdrawn the tumblers may not be in exactly the proper position, for although lined up properly with relation to each other 20 they may be a fraction of a tooth out of relative relation with the guide stud 50. This is rendered possible by reason of the fact that as the key 104 may turn freely it may be moved slightly after becoming 25 disengaged with the tumblers to withdraw it from the post 49. To remedy this and insure accurate alinement of the tumblers with reference to the stud 50, I employ an auxiliary key 109 which differs from the 30 key 104 only in that the cylindrical shell 110 extends into the body of the key in the same manner as the guard's key but has its slot 111 straight throughout its length. This key will remedy a disalinement to the 35 extent of a fraction of a tooth owing to the fact that the projecting end of its enlarged tooth is beveled, so that if the tumblers are slightly off in position, the beveled end will enter the alined recesses moving over the 40 tumblers into absolutely accurate position. This key cannot turn owing to the engagement of its slot with the stud 50.

Having described my invention what I claim as new and desire to secure by Letters 50 Patent of the United States, is—

1. In a permutation lock, a secondary tumbler having a predetermined operative position, a primary tumbler geared into the secondary tumbler and capable of moving the same to said predetermined position by its own motion to another predetermined position, the primary tumbler being provided with differently positioned steps one of which is engaged by the key ward according 55 to the length of the key ward, and means for disengaging the secondary tumbler from the primary tumbler so that the predetermined position of the primary tumbler may be changed and the secondary tumbler re-engaged.
2. In a permutation lock, a plurality of secondary tumblers having a common predetermined operative position, a primary tumbler geared into each secondary tumbler and capable of moving the same to said predetermined position by its own motion to another predetermined position, the said primary tumbler being provided with differently positioned steps one of which is engaged by the key ward according to the length of the key ward, and means for simultaneously disengaging all of the secondary tumblers from the primary tumblers so that the predetermined positions of the primary tumblers may be changed and the secondary tumblers reengaged.
3. In a lock, the combination with a bolt and a locking dog therefor, of means to release the dog, and key-operated tumblers to coöperate with the dog to retract the bolt.
4. In a lock, the combination with a bolt and a locking dog therefor, of means to release the dog, and key-operated gears for communicating motion to the dog to retract the bolt.
5. In a lock, the combination with a bolt and a locking dog therefor, of tumblers, and key-operated gears to first turn the tumblers into position to permit of the unlocking of the dog and then retract the bolt by coöperating with the dog, and means to release the dog.
6. In a lock, the combination with a bolt, a locking dog pivoted thereto and having a rack bar, of tumblers for preventing movement of the dog except when in predetermined position, and gears for moving the tumblers first into such predetermined position, wherein they are engaged by the rack bar upon the release of the dog and then impart motion to the dog to retract the bolt, and means to release the dog.
7. In a lock, the combination with a bolt having a tail provided with a rack bar, and a locking dog pivoted to the bolt and also provided with a rack bar, of a cam to release the dog, pivoted tumblers normally preventing movement of the cam, a second set of pivoted tumblers to secure the dog against movement except when in predetermined position, key-operated gears engaging the latter tumblers to turn the same first into their predetermined position to permit of the release of the dog under the action of the cam, such tumblers then being engaged by the rack bar of the dog, one of the said gears engaging the bolt tail rack, whereby motion is imparted to the bolt at a plurality of points to retract the same.
8. In a lock, the combination with a bolt and a locking dog therefor, of key tumblers adapted to be moved to predetermined positions to permit of the release of the dog, and a connection between the bolt and the tumblers whereby when the bolt is thrown the

70 75 80 85 90 95 100 105 110 115 120 125 130

2. In a permutation lock, a plurality of secondary tumblers having a common predetermined operative position, a primary tumbler geared into each secondary tumbler and capable of moving the same to said predetermined position by its own motion to another predetermined position, the said primary tumbler being provided with differently positioned steps one of which is engaged by the key ward according to the length of the key ward, and means for simultaneously disengaging all of the secondary tumblers from the primary tumblers so that the predetermined positions of the primary tumblers may be changed and the secondary tumblers reengaged.

3. In a lock, the combination with a bolt and a locking dog therefor, of means to release the dog, and key-operated tumblers to coöperate with the dog to retract the bolt.

4. In a lock, the combination with a bolt and a locking dog therefor, of means to release the dog, and key-operated gears for communicating motion to the dog to retract the bolt.

5. In a lock, the combination with a bolt and a locking dog therefor, of tumblers, and key-operated gears to first turn the tumblers into position to permit of the unlocking of the dog and then retract the bolt by coöperating with the dog, and means to release the dog.

6. In a lock, the combination with a bolt, a locking dog pivoted thereto and having a rack bar, of tumblers for preventing movement of the dog except when in predetermined position, and gears for moving the tumblers first into such predetermined position, wherein they are engaged by the rack bar upon the release of the dog and then impart motion to the dog to retract the bolt, and means to release the dog.

7. In a lock, the combination with a bolt having a tail provided with a rack bar, and a locking dog pivoted to the bolt and also provided with a rack bar, of a cam to release the dog, pivoted tumblers normally preventing movement of the cam, a second set of pivoted tumblers to secure the dog against movement except when in predetermined position, key-operated gears engaging the latter tumblers to turn the same first into their predetermined position to permit of the release of the dog under the action of the cam, such tumblers then being engaged by the rack bar of the dog, one of the said gears engaging the bolt tail rack, whereby motion is imparted to the bolt at a plurality of points to retract the same.

8. In a lock, the combination with a bolt and a locking dog therefor, of key tumblers adapted to be moved to predetermined positions to permit of the release of the dog, and a connection between the bolt and the tumblers whereby when the bolt is thrown the

- 6
- tumblers are simultaneously restored to such predetermined positions and are then returned to their original positions by the key.
- 5 9. In a lock, the combination with a bolt and a locking dog therefor having a rack bar, of pivoted tumblers, key operated gears by which the tumblers are moved to predetermined position to permit of the release of the dog, the said dog when released moving its rack bar into engagement with the tumblers and being maintained in such engagement during the retraction of the bolt, whereby when the bolt is thrown the tumblers are restored in unison to their predetermined position and then returned to their original position by the locking movement of the key operated gears.
- 10 10. In a lock, a plurality of rotatable tumblers having toothed openings, a key having teeth to coöperate with the tumbler teeth, and means on the lock to guide the key to move the said tumblers into predetermined position.
- 15 11. In a lock, a plurality of rotatable tumblers having central alined toothed openings, a key having its end in the form of a pinion adapted to enter the tumbler openings and engage the teeth, and means on the lock to guide the key to move the tumblers into predetermined position.
- 20 12. In a lock, a plurality of rotatable tumblers having central alined toothed openings, friction washers separating the tumblers and on which the latter are pivoted, a key post with which the tumblers are concentric and having a stud, and a key having a pinion to engage the toothed openings and a guide groove for the stud whereby as the key is inserted in the lock and turned the tumblers are successively picked up and rotated to bring the tumblers into predetermined position.
- 25 13. In a multiple key lock, a bolt, a plurality of two-part tumblers the respective parts whereof are constructed to be reset for co-action with different keys, a plate on which the resettable parts of the tumblers are mounted, means for moving the plate for resetting the tumblers, and a key-operated resetting lock for locking and unlocking and actuating the plate-actuating means.
- 30 14. In a multiple key lock, a bolt, a plurality of two-part tumblers the respective parts whereof are constructed to be reset for co-action with different keys, a plate on which the resettable parts of the tumblers are mounted, an eccentric for moving the plate for resetting the tumblers, and a key-operated resetting lock for locking and unlocking and actuating the eccentric.
- 35 15. In a multiple key lock, a bolt, a plurality of locking tumblers capable of co-operation with the bolt in different combinations, a plate controlling the resetting of the tumblers, an eccentric to move the plate, and a resetting key-lock operating the eccentric when unlocked and locking the eccentric against resetting the combination when locked.
- 40 16. In a multiple-key lock, a bolt, a plurality of two-part tumblers the respective parts of which are constructed to be reset for co-action with different keys, a plate on which the resettable parts of the tumblers are mounted, an eccentric for moving the plate, a key-operated resetting lock, and pinions interposed between the eccentric and resetting lock and moving the eccentric to connect and disconnect the two-parts of the tumblers when the resetting lock is operated by its key.
- 45 17. In a multiple-key lock, a bolt, a plurality of locking tumblers adapted to be set for co-action with different keys, a plate controlling the resetting of the tumblers, an eccentric to move the plate, a key-operated resetting lock operating the eccentric when unlocked and locking the eccentric against resetting the combination when locked, the arrangement of parts being such that the tumblers are locked against resetting for a different key until they are moved to position to unlock the bolt and the resetting lock operates the plate.
- 50 18. In a changeable key lock, a bolt, separately organized master tumblers and locking tumblers both of which are set to retract the bolt, a plate for resetting the locking tumblers, a guard's key for actuating the master-tumblers, a key for actuating the locking-tumblers to position for withdrawing the bolt, and a manager's key for actuating the master-tumblers to move the plate.
- 55 19. In a changeable key lock, a bolt, separately organized master tumblers and locking tumblers both of which are set to retract the bolt, a plate for resetting the locking tumblers, an eccentric actuating the plate, a guard's key for actuating the master-tumblers, a key for actuating the locking-tumblers to position for withdrawing the bolt, and a manager's key for actuating the master-tumblers to move the eccentric to actuate the plate.
- 60 20. In a lock, the combination with a bolt and a locking dog therefor, tumblers adapted to be moved to permit the release of the dog, a carrier on which the tumblers are mounted, key operated gears for turning the tumblers, a cam for sliding the carrier, and guard's tumblers adapted to be moved into predetermined position to permit of movement of the cam.
- 65 21. In a lock, the combination with a bolt and a locking dog therefor, rotatable tumblers adapted to be moved into predetermined position to permit the release of the dog.

- dog, a sliding plate provided with a post on which the tumblers are pivoted, key operated gears for turning the tumblers, a pair of cams having a pinion, a gear meshing 5 with the pinion, and a plurality of guard's tumblers to prevent movement of the cams, whereby when the guard's tumblers are in register in one position and the gear is turned the sliding plate will be moved by 10 one of the cams to disengage the tumblers carried thereby from the gears to reset the lock and when in another position and the gear is turned the dog is released by the other cam.
- 15 22. In a lock, the combination with a bolt and a locking dog therefor, of a plurality of tumblers adapted to be moved into predetermined position to permit the release of the locking dog, gears for turning 20 the tumblers, such gears having normally alined key openings one wall of which is straight while the other wall is stepped to coöperate with the bits of the key associated therewith.
- 25 23. In a lock, the combination with a bolt and a locking dog therefor, tumblers adapted to be moved into a position of register to permit the release of the dog, frictionally held gears for turning the tumblers, such
- gears having normally alined key openings, 30 each having one wall straight and substantially radial and the other stepped, and a key having a single bit to engage the straight walls to aline the openings.
24. In a lock, the combination with a plurality of tumblers each having an axial toothed opening provided with a recess and a guide post having a stud, of a key consisting of a shell having a pinion at its end, such pinion having a longitudinal slot for 35 the stud and a tooth adapted to enter the recesses of the tumblers as the key is inserted in the lock.
25. In a lock, the combination with tumblers each having a central toothed opening 40 provided with a recess, a post in the alined openings and having a stud, and a toothed key adapted to the tumbler openings and having a tooth to enter the recess and a longitudinal slot which coöperating with the 45 stud as the key enters the lock prevents 50 turning of the key.

In testimony whereof I affix my signature in presence of two witnesses.

BRUCE BORLAND.
